PULVERIZING MACHINE.

Application filed September 17, 1920, Serial No. 410,901. Renewed October 19, 1925.

The present invention relates to certain new and useful improvements in pulverizing machines of the class in which each consists of a rotatable barrel wherein the material 5 to be pulverized may be tumbled about with freely movable crushing bodies and be pulverized by contact therewith.

I am aware that mills have heretofore been produced comprising a barrel adapted 10 to revolve about its longitudinal axis which is so disposed to the horizontal that the included material will tend to travel on the lower side of the barrel from the receiving to the discharging end of the mill, and in 15 which the barrel is divided into a series of grinding compartments by screening partitions whereby the material is so classified that the coarser fragments are retained in the forward compartment while the finer 20 particles are passed progressively through the succeeding compartments towards the delivery end of the mill.

It is the especial object of this invention to provide improved screening partitions 25 whereby such classification of material will be more efficiently accomplished.

The devices by which I attain this object are fully set forth in the following specification and illustrated in the accompanying 30 drawings of which—

Fig. 1 is a vertical longitudinal section of the preferred embodiment of my invention, taken substantially on the line 1—1 of Figure 2.

Fig. 2 is a transverse view taken along the line II—II of Fig. 1.

Fig. 3 is a fragmentary sectional view taken along the line III—III of Fig. 1.

Like numerals refer to similar parts in 40 the several figures.

As shown in the drawings the numeral 1 indicates a barrel adapted to revolve about its longitudinal axis which is so disposed to the horizontal that material within the barrel 45 will tend to travel on the sides of the barrel from the receiving to the delivery end of the mill as the barrel revolves. To the barrel 1 is attached the bearing rings 2 and 3 which bear upon the rollers 4 and 5 to support the barrel for rotation. The rollers 4 and 5 are mounted in suitable journal 50 bearings 6 and 7 which are supported upon the foundations of the mill. To the barrel 1 is attached a ring gear 8 which is engaged

by a pinion 9. The pinion 9 is mounted upon a power shaft from which power is derived to revolve the barrel. The upper end of the barrel 1 is closed by a plate 10 to which is secured a cylindrical extension 11. The extension 11 is journaled in a pillow block 12 supported upon the foundation castings 13. The pillow block 12 is provided with the customary removable cap 14 in which is formed a lubricant receptacle 15. 16 is a ball bearing interposed between the outer end of the pillow block 12 and the flange 17 of the cylindrical extension 11 to prevent longitudinal movement of the barrel. The cylindrical extension 11 and the plate 10 are pierced by a central bore through which 70 extends a cylindrical trough 18 formed at the lower end of a feed hopper 19. Positioned within the cylindrical trough 18 is a screw conveyor 20 to the extended shaft of which is attached a suitable pulley 21 adapted to be connected with any convenient source of power to rotate the screw conveyor 20 and thereby transfer material from the feed hopper 19 to the interior of the barrel 1. The lower end of the barrel 1 is closed 80 by a transverse wall 22 provided with screening apertures adapted to permit the escape of the finely pulverized material from the interior of the mill while retaining the over sized material for further grinding. 85 The size, form and arrangement of the screening apertures are subject to wide variation to suit the requirements of material of different characters and the desired fineness of the product. These apertures pref- 90 erably expand outwardly to prevent the lodgment therein of fragments of material and the consequent choking of the screen.

As the fineness of grinding is directly related to the duration of time the fragments 95 of material are retained within the mill, I prefer to form the barrel 1 with such a taper that when mounted upon a horizontal axis, as shown in Fig. 1, the rate of flow of the material longitudinally of the mill will 100 carry said material to the discharge ends at the precise moment it is pulverized to the desired degree of fineness. It is apparent that if the taper of the mill were increased it might be necessary to incline the 105 axis of rotation upwardly to prevent the material flowing too rapidly through the mill, and if the sides of the barrel were made

less tapering, or parallel, it would be necessary to incline the axis downwardly to produce the desired rate of travel.

The friction of the material against the sides of the barrel cause the lower part of its mass to be moved upwardly with the ascending side of the barrel, while the upper portion of the mass slides downwardly, maintaining a continuous orbital movement of the fragments of which the mass is composed, and the friction due to this movement is an important element in producing a grinding action of the mill. The grinding balls, being of greater specific gravity than the fragments of material which is being pulverized, gravitate toward the lower part of the mass and become buried beneath the lighter material. These balls are carried upward with the side of the barrel to an elevation depending upon the angle of repose which is a characteristic of the material under treatment, and to the centrifugal force due to the velocity of rotation. At the point of maximum elevation the material falls away from the side of the barrel and the grinding balls roll upon the surface of the mass, striking fragments of material lying upon the lower side of the barrel to break them by their percussive action, thereby materially assisting in pulverizing the material.

When a mass composed of freely movable fragments of various sizes but of the same specific gravity is agitated, the finer particles tend to slip through the interstices between the larger fragments, and the larger fragments tend to float to the surface, resulting in a more or less complete stratification of the mass relative to the size of its component fragments. Due to the tendency to stratification, and the inclination of the lower side of the barrel, the finer particles of material sink to the bottom of the mass and travel longitudinally of the mill tending to accumulate against the surface of the screen 22. Owing to the slippage of material against the surface of the mill this accumulation of fine material slides across the screening apertures as the mass is carried upwardly and the smaller fragments are forced through these apertures by the weight of the material upon them. From the point of maximum elevation the material rolls downwardly across the face of the screen and the small fragments pass through the screening apertures while the larger fragments are retained within the pulverizing chamber.

As the larger fragments of the material which is to be pulverized can only be broken by contact with relatively large and heavy grinding bodies, as the most efficient reduction of the finer particles is accomplished by a large number of relatively small grinding bodies, and as the size of the component

fragments of the material within the mill is progressively reduced from the receiving towards the discharge end, it is apparent that a corresponding classification of the grinding bodies is desirable. To accomplish such classification I have divided the barrel 1 into a series of grinding compartments A, B, C and D by the transverse screens 23, 24 and 25 which are similar to the screens 22 but are respectively provided with apertures of progressively decreasing dimensions the screens nearest the receiving end having the largest apertures. By this arrangement of screens the material in the successive compartments of the mill is classified relative to the size of its component fragments, and each grinding compartment is provided with grinding bodies of a size appropriate to the most efficient grinding of the material in said compartment.

I am aware that grinding mills have been proposed with transverse screens dividing the interior of the barrel into a series of pulverizing chambers, but, as heretofore constructed, the pressure of material upon the rearward side of the screen tends to prevent the movement of fragments through the apertures of the screen thereby interrupting the flow of material through the mill. It is desirable to provide at the rear face of the screening partition of a mill, such as this, some means adapted to engage the material, which tends to back up against the face of the screen, and to throw the material forwardly within the barrel away from the partition apertures. To overcome this difficulty I have provided at the rearward side of the screens 23, 24 and 25 a plurality of radially extending wings 26 which are inclined to the surface of the screen as shown in Fig. 3, and which tend, as the mill revolves, to throw the material away from the rearward side of the screen in the manner of a plowshare. It will be noted that the wings have outer portions which extend over the face of the screens, or are inclined to the screen surface. Thus, as the barrel revolves, the wings do not pick up the material, but merely deflect the same. Moreover, there is formed at the concave side of each wing a pocket, as is shown in Figure 3, adapted to receive the material passing through the screening apertures. The inclination of the wings serves to prevent the deflected material from immediately crowding or baking up against the screen, as would occur if the wings merely projected outwardly from the face of the screen without inclination. By the eddying movement thus caused in the material adjacent the rearward side of the screens 23, 24 and 25, as diagrammatically illustrated in Fig. 3, there is created a series of voids, a, b, and c into which the material of the preceding

chambers may freely flow through the apertures of the respective screens, materially increasing the efficiency of the screen and achieving the desired classification of the 5 grinding bodies without interrupting the flow of material through the mill.

At the delivery end of the barrel 1 I have provided a receiving chamber 27 having flanges 28 which forms a dust tight 10 joint with the sides of the barrel 1 and which is provided with a spout 29 to conduct the material from the mill to any preferred destination.

What I claim is—

15 1. In a pulverizing mill of the class described, the combination with an approximately horizontal barrel adapted to revolve about its longitudinal axis, of a transverse partition dividing the interior of the barrel into grinding chambers, said partition having a plurality of screening apertures, and means extending from approximately the periphery of the partition inwardly on the rearward face thereof adapted to engage material adjacent said apertures and to deflect it longitudinally of the mill away from the apertures.

20 2. In a pulverizing mill of the class described, the combination with an approximately horizontal barrel adapted to revolve about its longitudinal axis, of a transverse partition forming a grinding chamber, said partition having a plurality of screening apertures, and means projecting from the rear face of the partition extending across the same and having a laterally directed portion spaced from the surface of the partition, said means being adapted to engage material adjacent said apertures and deflect the same longitudinally of the mill away from said apertures.

25 3. In a pulverizing mill of the class described, the combination with an approximately horizontal barrel adapted to revolve about its longitudinal axis, of a transverse partition forming a grinding chamber, said

partition having a plurality of screening apertures, a deflecting wing projecting from the rear face of the partition and extending inwardly from adjacent the periphery of the same, said deflecting wing having a laterally projecting portion spaced from the face of the screen, the wing being adapted to engage material adjacent said apertures and deflect it longitudinally of the mill away from said apertures.

4. In a pulverizing mill of the class described, the combination with an approximately horizontal barrel adapted to revolve about its longitudinal axis, of a transverse partition dividing the interior of the barrel and forming a grinding chamber, said wall having a plurality of screening apertures, and means projecting from the rear face of the partition and extending inwardly from substantially the periphery of the same, said means being inclined to the face of the partition and being adapted to engage material adjacent said apertures and deflect it longitudinally of the mill away from said apertures.

5. In a pulverizing mill of the class described, a rotatable barrel, a transverse partition having a plurality of screening apertures, and a series of substantially radially extending wings on the rear surface of said partition having portions projecting laterally over the surface of the screen and spaced from said surface.

6. In a pulverizing mill of the class described, a rotatable barrel, a transverse partition in said barrel forming a grinding chamber, said partition having a plurality of screening apertures therein, and a plurality of radially extending wings projecting from the rear face of said partition, said wings being inclined to the face of the partition.

In testimony whereof, I affix my signature.

DUDLEY T. FISHER.
